STRIPPING MACHINE

Lyle E. Shaner, Naugatuck, Conn., assignor to
 Box Blank Corporation, New York, N. Y., a
 corporation of Delaware

Application June 22, 1944, Serial No. 541,608

17 Claims. (Cl. 164—87)

1

This invention provides a machine for the mechanical separation of scrap and blanks cut from sheets of cardboard, paperboard and similar material, hereinafter briefly referred to as "board."

Blanks for cartons and containers are customarily cut in multiple from large sheets of board. The sheets are passed through a cutting and scoring machine equipped with a plurality of cutting and scoring knives. The edges of the cutting knives outline the contour of the blanks to be cut and cut through the board separating the blanks from the remainder of the sheet, the so-called scrap. The scoring knives are so adjusted as not to cut through the board, but to produce depressions therein, so-called score lines, along which the blank is later folded.

The number of blanks cut from a sheet varies, depending on the size of the sheet and the size of the blank. Sheets containing nine, twelve or fifteen blanks are commonly used.

To prevent the blanks from separating in the cutting machine the cut lines are interrupted at various points so as to leave the several blanks connected with the scrap by narrow necks or bridges having a width of approximately one thirty-secondth of an inch. The necks or bridges are left unsevered by the cutting knives which at the appropriate points are provided with indentations or nicks.

After the sheets are cut and scored they are usually stacked up in well aligned stacks of considerable thickness and then stripped to separate the scrap from the blanks. The stripping is customarily done by hand by chopping away the scrap from the blanks by hand tools somewhat resembling a hatchet or a hammer.

The manual stripping entails various disadvantages. The interruption of the otherwise completely mechanized process of making a carton or container by a manual operation constitutes a rather undesirable bottleneck in the production. Manual stripping is expensive because of the requirement of skillful workers. It is wasteful because an occasional ill-directed blow with the stripping tool leads to damage to a considerable number of blanks which have to be discarded. Thus hand stripping introduces an unpredictable loss factor into the production. Another undesirable factor is the disarrangement of the blanks which have to be re-stacked for feeding into container forming machines.

The invention provides a machine for automatically and continuously stripping blanks. A preferred form of the machine consists in substance of a movable die plate, preferably of rel-

2

atively thin material such as sheet steel. The die plate contains apertures through which the blanks are forced by punches while the scrap is being clamped to the surface of the die plate. The die plate is movable to bring its apertures into registry with the punches for a convenient removal of the scrap resting on the plate. According to one form of the invention the die plate is moved in tracks from beneath the punches onto a downwardly curved path to shed the scrap. According to another form of the invention a die plate having therein a plurality of sets of apertures is moved intermittently in one direction so that blanks are stripped through one set of apertures while the scrap is removed from another set of apertures of the die plate.

The objects, features and advantages of this invention will appear more fully from the detailed description which follows accompanied by drawings showing for the purpose of illustration preferred embodiments of the invention.

The invention also consists in certain new and original features of construction and combination of parts hereinafter set forth and claimed.

Although the novel features which are believed to be characteristic of this invention will be particularly pointed out in the claims appended hereto, the invention itself, its objects and advantages and the manner in which it may be carried out may be better understood by referring to the following detailed description taken in connection with the accompanying drawings forming a part thereof, in which:

Fig. 1 is a side view of a stripping machine embodying my invention;

Fig. 2 is an enlarged side view of an air valve of the machine shown in Fig. 1;

Fig. 3 is a side view, partly in section, of the top portion of the machine shown in Fig. 1, a section being taken on line 3—3 of Fig. 4;

Fig. 4 is an elevational end view of the section of the machine shown in Fig. 3, a section being taken on line 4—4 of Fig. 3;

Fig. 5 is a fragmentary plan view of a plunger head plate;

Fig. 6 is a fragmentary plan view of a cut and scored sheet of board ready for stripping in the machine;

Fig. 7 is a fragmentary plan view of a die plate;

Fig. 8 is a fragmentary plan view of a supporting frame work for reinforcing the die plate;

Fig. 9 is a fragmentary plan view of a top plate for the frame work shown in Fig. 8;

Fig. 10 shows in detail a pneumatically operated end stop for properly locating the sheets of

board in the machine shown in Figs. 1, 2 and 4; and

Fig. 11 is a simplified plan view of a stripping machine having a rotary multiple die plate.

A machine base 11 has four posts 12 provided with vertical guideways 13. A plunger frame 14 having laterally extending guide blocks 15 is mounted in the guideways 13 for vertical movement. The plunger frame 14 is provided with four lugs 16 having pins 17 therein for connection to the lower ends of plunger rods 18. The upper ends of the plunger rods 18 are connected to cranks 19 by pins 20, the cranks being fixedly mounted on common shafts 21 and 22.

Shaft 21 is mounted in bearings in the upper ends of two posts 12 at the receiving end of the machine and is driven by a chain 23 trained over a chain gear 24 on the end of the shaft 21. A bevel gear 25 mounted on the shaft 21 by a pin 26 meshes with a second bevel gear 27 secured to a shaft 28 by a pin 29. The shaft 28 rests in bearings in the ends of brackets 30 at the upper ends of the posts 12. A second set of bevel gears 31 and 32 are secured to the end of the shafts 28 and 22 at 33 and 34, respectively, and drive the shaft 22 at the same rate as shaft 21, but in the opposite direction.

The plunger frame 14 is provided with a recess 35 for insertion therein of a relatively thick and rigid plunger head plate 36, which is held in place by an end plate 37 secured by bolts 38.

The plunger head plate 36, also shown in Fig. 5, has a great number of mounting apertures 39. Bolts 40 provided with washers 41 and wing nuts 42 extend through certain of these mounting apertures 39, and hold punches 43 in place. The punches 43 may be made of hardwood, and are assembled on the plunger head plate 36 in an arrangement corresponding to the arrangement of the blanks in the sheet of board to be stripped. The punches 43 have recessed holes 44 for accommodating the heads of the bolts 40. The bolts 40 are smaller than the mounting apertures 39 in the plunger head plate 36 and preferably also smaller than the recessed holes 44 in the punches, so as to permit any number of punches to be mounted in any desired arrangement on the same head plate.

Hold down members 45 extend through other mounting apertures 39 in the plunger head plate. Each hold down member comprises a sleeve 46 having an enlarged head 47 at one end and a screw thread at the other. A presser foot 49 is vertically slidable in the sleeve 46, and is urged downwardly by a helical spring 50 bearing with one end against the enlarged head 47 of the sleeve 46 and with the other against a flange 51 on the presser foot. The downward movement of the presser foot under action of the spring 50 is limited by a pin 52 striking against the upper end of the sleeve 46. The hold down members hold the scrap in place during the stripping operation, as will later appear.

A die plate 53 of relatively thin flexible sheet steel is mounted for sliding movement in a recess 54 of a die plate supporting frame 55.

The die plate supporting frame 55 has blocks 56 engaging the guideways 13 and guiding the frame for vertical movement. The die plate supporting frame 55 rests on four helical springs 57 mounted in pockets 58 in the base 11. The upper ends of the springs are fitted in similar pockets 59 on the underside of the die plate supporting frame 55. The spring mounting of the die plate permits of a downward movement of

the die plate whenever the force exerted on the die plate is greater than the force of the springs 57.

The die plate 53 is slidable in the die plate supporting frame in a substantially horizontal direction and may be moved, either partially or entirely, onto a downwardly curved track 60 by a set of oscillating arms 61. The arms 61 are pivotally mounted on the base 11 at 62 and carry at their upper ends pins 63 engaging elongated holes 64 in lugs 65 on a transverse bar 66 secured to the end of the die plate 53. The transverse bar 66 has a hollow channel 67 therein communicating with the atmosphere through suction ports 68. Suction may be applied at the ports 68 by withdrawing air from the channel 67 through a flexible hose 69 connected with one end to the channel by a coupling 70 and with the other end to a control valve 71 at 72.

20 The upward movement of the die plate supporting frame 55 under the action of the springs 57 is limited by adjustable eccentric stops 73 having handles 74 and mounted on the posts 12 at 75.

25 The die plate is shown in plan view in Fig. 7, and contains a plurality of die apertures 76 arranged according to the location of the blanks in the sheet of board to be stripped. A sheet of board is shown in plan view in Fig. 6.

30 A die plate supporting structure is arranged underneath the punches 43, and consists of a rigid framework 77 built up from strips of flat steel mounted in an outer frame 78. The outer frame 78 rests in recesses 79 in the base. A top plate 80 is mounted on the framework 77 and its outer frame 78, and has in it a plurality of apertures 173 arranged to register with the apertures 76 in the die plate 53 and the punches 43.

35 When during the stripping operation a certain amount of force is exerted on the die plate 53, the die plate and the die plate supporting frame 55 move downwardly against the action of the springs 57 until the die plate rests on the supporting structure 77, 78, 80 preventing flexing of the relatively thin die plate 53.

40 Sheets of board 81 are fed into the stripping machine at the receiving end, a portion of the die plate supporting frame 55 being machined away at 82 to permit passage of the sheets.

45 The sheet 81 rests with its front edge 83 against a releasable stop mechanism 84 shown in greater detail in Fig. 10. The stop mechanism comprises a cylinder casing 85 having a piston 86 movable therein connected to a piston rod 87. A helical spring 88 bears against the piston 86 and the top wall of the cylinder casing, and urges the piston downwardly. A piston rod has at its lower end a stop 89 normally resting on the top surface of the die plate 53. The stop 89 limits the forward movement of the sheet 81 fed into the machine.

50 The cylinder casing 85 has an extension 90 provided with an annular recess 91 into which a forked wedge 92 fits. The wedge 92 holds the cylinder casing in place, and is clamped 55 to the lower surface of the plunger head plate 36 by a set screw 93.

55 A flexible hose connection 94 leads from the cylinder casing 85 to a control valve 95 having a lever 96 operating the stem 97 of a valve member. The valve member opens and closes the passage in the valve between the hose 94 leading to the cylinder casing 85 and a pipe 98 leading to a source of suction pressure, such as a pump (not shown). The valve lever 96 is operated by a cam 99 mounted on the shaft 22 to which also

the crank 19 is secured. The cam 99 has an elevated portion 100 causing the valve 95 to open to admit suction to the cylinder casing 85. The remainder 101 of the cam circumference is depressed and causes the valve 95 to close, disconnecting the cylinder casing 85 from the source of suction and venting the interior of the cylinder to the atmosphere to a vent port 102 in the valve. While the interior of the cylinder casing 85 is vented, the spring 88 forces the stop 89 downwardly until it rests against the top surface of the die plate 53. When the elevated portion 100 of the cam 99 acts on the valve 95, air is withdrawn from the cylinder casing 85 causing the stop 89 to be raised from the die plate 53 shortly before the die plate is moved onto the curved track 60 for the removal of the scrap.

Blanks removed from sheets of board drop through the apertures in the die plate supports 77, 78 and 80 and accumulate on a receiving platform 103 vertically movable by means of chains 104 trained over sprocket spools 105 on a shaft 106. The shaft 106 is mounted in bearings 107 in the base 11, and carries at one end a worm gear 108 meshing with a worm 109 on a transverse shaft 110. The transverse shaft is mounted in bearings 111 and carries a ratchet gear 112 secured by a pin 113 and an oscillating lever 114 held in place by a collar 115 secured by a pin 116. The oscillating lever 114 carries a pawl 117 engaging the teeth of the ratchet gear 112. The oscillating lever 114 is operated by a rod 118 linked to an oscillating arm 119 at 120. The oscillating arm 119 is pivoted at 121 on the base 11 and is operated by a further rod 122 connected to a triple armed lever 123 at 124. The triple armed lever 123 is pivoted on a bracket 125 at 126, and is operated by a rod 127 leading to the end of a single armed lever 128 pivoted to the base 11 at 129. The single armed lever 128 carries a pin 130 engaging the internal cam race 131 of a cam member 132 mounted on a shaft 133. Cam 132 and shaft 133 are driven by a chain gear 134 around which a chain gear 135 is trained leading to a similar chain gear 136 on the shaft 21.

When the shaft 21 is rotated the cam member 132 is driven by the chain 135 at the same rate as the shaft 21 causing the lever 128 to oscillate. The oscillating movement of the lever 128 is transmitted to the triple armed lever 123 through the rod 127, and thence through rod 122, arm 119 and rod 118 to the pawl and ratchet 112, 117 for lowering the platform 103 by the thickness of one blank for each revolution of the cam 132.

The triple armed lever 123 further operates a feed conveyor 137 by a push rod 138 linked to the triple armed lever 123 at 139. The conveyor 137 is slidable in horizontal tracks 140, and comprises a plurality of parallel belts 141 trained over pulleys on shafts 142 and 143. The assembly of conveyor belts 141 is connected to a vertically extending lug 144 to which the push rod 138 is hingedly connected.

The feed conveyor 137 normally forms part of an automatic cutting and scoring machine or an automatic printing, cutting and scoring machine to which the stripping machine may be attached as a terminal unit. Such automatic machines are well known in the industry, and a detailed description of their function and structure is not required for an understanding of this invention. Suffice it to say, that printed, cut and scored sheets of boards are deposited on the conveyor mechanism 137, which is then moved

underneath the elevated plunger heads 14, 36 carrying the punches 43, while the pulleys on the shaft 142 and 143 of the conveyor are at rest. The conveyor belt assembly 141 is then withdrawn from underneath the plunger of the stripping machine while simultaneously the conveyor belts are driven in clockwise direction causing the sheet on the conveyor to be thrown off and placed on the die plate 53 with the front edge 83 of the sheet 81 resting against the stop 89. After the conveyor assembly 141 has reached its retracted position shown in Fig. 1, the conveyor belts 141 come to rest and a new sheet of board is deposited thereon.

The flexible die plate 53 is horizontally movable into and out of registry with the plungers 43 by the oscillating arms 61, one arm being preferably mounted on either side of the machine. The oscillating arms 61 are pivotally mounted to the base 11 at 62, and carry a pin 145 engaging the internal race 146 of a cam member 147, there being preferably one cam for each lever 61. The cam members 147 are mounted on a common shaft 148 carrying a chain gear 149 driven by a chain 150 from a second chain gear 151 on the shaft 22.

As the levers 61 are swung clockwise into the end position indicated in dash dot lines at 61', the die plate 53 and the scrap resting thereon is moved onto the curve track 60, causing the scrap to be shed off the die plate 53.

The scrap is retained on the die plate 53 during its movement by suction applied at the ports 68 at the end of the die plate. The valve 71 controlling the application and the release of section at the ports is operated by the oscillating lever 61 through a linkage 152 pivotally connected to the lever 61 at 153, and to a control arm 154 on the valve at 155.

40 A suction duct 156 leading to suitable source of suction, such as a pump (not shown), is connected to the valve at 157. The valve is proved with a vent port 158 leading to the atmosphere and with a hose connection 72 for the suction hose 69 leading to the suction ports 68 in the die plate.

In the position shown in Fig. 1, suction is applied at the ports 68 firmly retaining the sheet or scrap on the die plate. The suction is maintained while the die plate is being moved from underneath the punches and relieved as the oscillating levers approach the end position 61'. In this position the suction ports 68 are disconnected from the source of suction and admit atmospheric air through the vent port 158.

60 A supplementary tray plate 159 for blanks rests normally on rollers 160 to one side of the stripping machine as shown in Fig. 1. It is guided in tracks 161 in the base 11 and may be moved into a position between the punches 43 and die plate 53 by a handwheel 162 provided with a handle 163. The handwheel is mounted on a shaft 164 and operates a friction roller 165 engaging the plate 159. In the position below the punches 43 the tray plate 159 is supported by rollers 166 mounted on brackets 167 and serves as a temporary receiving platform for blanks which are being separated from the sheet, permitting removal of the stacks of blanks 168 from the regular receiving platform 103 without interruption of the operation of the machine.

65 The layout of the blanks in a sheet of board is shown in Fig. 6. The blanks 168 are cut along lines 169, the cut lines being interrupted by narrow necks or bridges 170 which maintain the

blanks in connection with the surplus material or scrap 171 surrounding the blanks. The blanks 168 are further scored along score lines 172 along which the blanks are later folded to form cartons.

During the stripping operation the narrow necks or bridges 170 are severed to separate the individual blanks from the scrap. The stripped scrap remaining on the die plate 53 forms an open net work or mesh.

The die plate 53 on which the sheet 81 rests during the stripping operation contains die apertures 76 arranged in the same pattern which the blanks 168 assume in the sheet of board 81. The configuration of the apertures is similar to that of the cut lines defining the outer edges of the blank. However, I prefer to make the apertures in the die plate slightly narrower in width, or length, or both width and length, so as to cause the blank to be slightly flexed or deformed while the blank is forced through the respective die plate aperture 76. I find that this flexing of the blank greatly facilitates the severance of the necks or bridges which connect the blanks 168 with the remainder of the sheet 81.

Whether only the length or the width of the die plate aperture, or whether both dimensions should be made shorter than the corresponding dimension of the blank depends on the particular form of the blank. In the illustrated form of blank, which is the blank for a cigarette carton, I prefer to make the length *a*, as well as the width *b*, slightly shorter than the corresponding dimensions of the blanks 168.

The supporting top plate 80 has apertures 173 therein, which are larger than the blanks 168 so as to permit the blanks to drop through the apertures 173 freely.

The apertures 76 in the die plate 53, and the apertures 173 in the support plate 80, may be machined simultaneously. This is preferably done by superimposing two sheets of steel, one for the die plate 53, and one for the support plate 80, and machining apertures of the outline of the die plate apertures 76 into the two superimposed plates. Thereafter the plates are separated and the apertures in the support top plate 80 enlarged, until the desired size and form of the apertures 173 is reached. The configuration of the apertures 173 need be less detailed than that of the die plate apertures 76, as is also shown in the drawings. The procedure of machining plates 53 and 80 together insures a proper registry of the respective apertures.

The framework 77 in the frame 78 reinforcing the top plate 80 is so laid out as to support the relatively thin top plate 80 at all vital points.

The top plate 80 may be omitted and the reinforcing structure consisting of the framework 77 and the outer frame 78 be used as the immediate support for the die plate. However, I find it preferable to build up a reinforcing supporting structure for the die plate 53 out of a framework 77 and frame 78, and a top plate 80 since the surface of the sheet metal top plate 80 is smooth and requires no machining and permits of the use of a supporting framework of great tolerances and consequent inexpensive construction, whereas a framework of more detailed layout would be required properly machined to the necessary surface smoothness, if the top plate 80 were omitted.

The fitting of the machine for a new type of sheet and blank may be carried out in the following manner:

The plunger head plate 36 is removed from the

machine and placed bottom side up. The corresponding die plate 53 is placed upon it, also with its bottom side up. The punches 43 are then placed upside down into the spaces defined by the die plate apertures 76, adjusted so as to leave ample clearance between the outer edges of the punches and the edges of the die plate apertures 76, and then secured to the plunger head plate 36 by means of the bolts 40, washers 41 and wing nuts 42. After the punches are in place, the die plate 53 is removed from the surface of the plunger head plate 36 and the hold-down elements 45 are secured between the punches so as to engage the scrap portions of the sheet to be stripped.

After the punches 43 and the hold-down elements 45 are assembled with the plunger head plate 36, the head plate is slid into the plunger frame 14 and secured therein by the end plate 37 and bolts 38. Thereafter, the rigid support 77, 78 for the die plate is placed in the machine and finally the die plate 53 slid into its guideways or recesses 54 in the die plate supporting frame 55, whereafter the machine is ready for a final check and operation.

The operation of the machine is as follows:

While the cranks 19 of the machine and the plunger 14, 36 and punches 43 are near their uppermost position, the feed conveyor 137 carries a sheet 81 into the space between the die plate 53 and the plunger assembly 43, 36, and deposits it on the die plate 53 while the conveyor 137 recedes. The front edge of the blank 81 rests against the stop 89 of the pneumatically operated stop mechanism, which during this phase of the operation is in its lowermost position.

As the cranks 19 continue to revolve, the left hand crank in Fig. 3 rotating clockwise, and the right hand crank, rotating counterclockwise, the plunger approaches the sheet 81 on the die plate 53. The hold-down elements 45 on the plunger make contact with the sheet first and clamp its scrap portions firmly against the die plate 53. Shortly thereafter the punches 43 make contact with the blank portion 173 of the sheet. The force exerted on the die plate 53 causes the die plate 53 and its supporting frame 55 to move downwardly against the action of the helical springs 57 until the die plate 53 comes to rest on the top plate 80 of the rigid support 77, 78.

The punches then force the blanks through the die plate apertures 76 separating the blanks 168 from the scrap portions of the sheet 81 which remains firmly clamped to the top surface of the die plate 53. The blanks 168 drop through the apertures of the die plate supporting structure 77, 78, 80, and form stacks of blanks on the receiving platform 103. As herein before described, the receiving platform 103 moves downwardly by an amount equal to the thickness of one blank during each revolution of the crank 19, so as to maintain the top level of the stack of blanks 168 at a constant distance from the die plate support 78 and 80.

As the cranks 19 continue their revolutions, the punches 43 are withdrawn from the die plate apertures 76, and the die plate returns to its uppermost position under action of the springs 57 until the guideways 54 in the die plate supporting frame 55 registers with the corresponding guideways in the curved tracks 60. The uppermost position of the die plate supporting frame 55 is adjustable by means of the eccentric stops 73 on the posts 12. In the elevated position there is ample clearance between the die plate 53 and the supporting structures 77, 78, 80 preventing

the die plate in the event of accidental deformation or bending of relatively narrow projections from engaging the supporting structure during the following withdrawal from beneath the punch assembly.

The cam member 141 moves the oscillating arms 61 clockwise moving the die plate 53 from underneath the punches for disposal of the scrap resting thereon. During the withdrawal of the die plate 53 from underneath the punches 43, the scrap is held on the die plate by suction exerted at the suction ports 68.

As the die plate 53 approaches its outermost position, the control valves 71 controlling the suction is moved to a position in which the suction ports are disconnected from the suction conduit 156 and vented to the atmosphere through the vent port 158.

The release of the suction, the inertia of the moving scrap and gravity cause the scrap to slide off the curved die plate 53, which thereafter is returned by the levers 61 moving in counter-clockwise direction to a position of registry of the die plate apertures 76 with the punches. During the return movement of the die plate 53, suction is restored at the ports 68, causing the new sheet about to be deposited to adhere firmly to the die plate 53.

As the cranks 19 approach the uppermost position, the feed conveyor 131 is again advanced into the space between the elevated plunger assembly 36, 43 and the die plate 53, and the cycle of operation is repeated.

After a sufficient number of blanks has accumulated on the receiving platform 163 the auxiliary tray 159 is moved underneath the die plate support 78, 80 by turning the handwheel 162. In this position the auxiliary tray receives the blanks 168 and permits removal of the stacks of blanks 163 from the receiving platform without interruption of the continuous operation of the machine.

A form of machine in which the die plate is moved intermittently in one and the same direction is shown in plan view in Fig. 11.

A crank-driven power press has a base 174 upon which is mounted a substantially vertical standard 175 supporting a table 176 and a head structure 177 carrying the two bearings 178 and 179 for a crankshaft 180. The crankshaft has a flywheel 181 connected to one end and carries a crank portion at the other engaging the top bearing 182 of a substantially vertical plunger rod. The plunger rod moves a plunger 183 mounted between guideways 184 and face plates 185 secured to the head structure by bolts 186.

A plunger frame 187 is carried by the lower end of the plunger 183 and has secured to its underside a plunger headplate and punches similar to the headplate and punches shown in Figs. 1, 3 and 4, the headplate being held in place by an end plate 188 secured by bolts 189.

A rotary die plate 190 is mounted underneath the plunger and punch assembly and is rotatable about a center post 191. The rotary die plate contains two sets of die apertures 192, one being in registry with the punches on the plunger assembly and therefore not visible in the drawings, the other set being diametrically opposite the first set. Notches 193 at the periphery of the die plate 190 cooperate with a periodically operated arresting mechanism 194 insuring proper registry of the sets of die apertures with the punches.

The plunger and punch assembly is periodi-

cally moved up and down by the crank on the crankshaft 180 driven by a belt 195 trained around the flywheel 181 and a pulley 196 on a motor 197. Suitable mechanism, also driven by the motor and not shown in the drawings, turns the rotary die plate 190 one-half revolution about the post 191 after each down-and-up-stroke of the plunger 183 whereafter the arresting mechanism 194 arrests the die plate in the proper position with respect to the punches.

A feed conveyor 131 having individual belts 141 trained around pulleys on a front shaft 143 feeds scored and cut sheets of board into the space between the raised punches and the die plate 190 to deposit them over the respective set of die apertures 192. The blanks are then removed from the sheet in the same manner as described in connection with the operation of the machine shown in Figs. 1, 3 and 4. After the punches have cleared the die apertures 192 the die plate 190 is rotated at 180° about the center post 191 carrying the scrap with it for removal by a conveyor belt 198 the lower run of which frictionally engages the upper surface of the die plate 190 and sweeps the scrap off.

A particular feature of this invention is that the novel stripping machine may be added as a separate unit to printing, scoring and cutting machines of conventional construction and may be so timed as to operate in synchronism therewith. Thus the production of a carton blank becomes a continuous mechanized process uninterrupted by any manual operations as were heretofore required for the separation of blanks from scrap. This is a particular feature of my invention contributing to a material reduction of the cost of the blanks in connection with the further feature of elimination of spoilage of blanks which is unavoidable where the manual method of stripping is used.

Obviously the present invention is not restricted to the specific forms of the machines herein shown and described. Various changes of design and construction may be made. Features may be added or omitted and substitutions of similar and equivalent mechanical elements may be made for the ones shown. Such changes and modifications will be obvious to persons skilled in the art and manifestly do not involve a departure from the spirit and teaching of this invention.

What is claimed is:

1. A machine for removing from blanks pre-cut from a sheet of cardboard, paperboard, and the like, scrap adhering to said blanks, comprising, a movable die plate for receiving sheets of board, said die plate having apertures therein; means for forcing the blanks through said apertures; means for engaging said scrap while the blanks are being forced through the die plate apertures; and means for moving said die plate from one position in which blanks are forced through its apertures to a different position for the removal of the scrap therefrom.

2. A machine for removing from blanks pre-cut from a sheet of cardboard, paperboard, and the like, scrap adhering to said blanks, comprising, a reciprocating plunger head; a plurality of punches mounted on said plunger head for engaging said blanks; hold down means for engaging said scrap; a movable die plate having apertures therein; and means for moving said die plate into and out of registry with said punches for removal of scrap from said die plate.

3. A machine for removing from blanks pre-cut from a sheet of cardboard, paperboard, and

the like, scrap adhering to said blanks comprising, a reciprocating plunger head; a plurality of punches mounted on said plunger head for engaging said blanks; hold-down means for engaging said scrap; a die plate support underneath said plunger head; a movable die plate overlying said support; and means for moving said die plate out of registry with said punches for removal of the scrap from said die plate.

4. A machine for removing from blanks pre-cut from a sheet of cardboard, paperboard, and the like, scrap adhering to said blanks comprising a reciprocating plunger head; a plurality of punches mounted on said plunger head for engaging said blanks; a plurality of hold-down elements for engaging said scrap; a die plate support underneath said plunger head; a curved track; a flexible die plate overlying said support; and means for moving said die plate from underneath said plunger onto said curved track for shedding the scrap off said die plate.

5. A machine for removing from blanks pre-cut from a sheet of cardboard, paperboard and the like, scrap adhering to said blanks, comprising a reciprocating plunger head; a set of punches mounted on said head for engaging the blanks of a sheet; hold-down means for engaging the scrap of the sheet; a die support underneath said plunger head, said support having apertures permitting the blanks to drop therethrough; a die member having therein a plurality of sets of die apertures, each set corresponding to said set of punches; said die member overlying said support; and means for moving said die member relatively to said support for bringing said die apertures successively into registry with said punches.

6. A machine for removing from blanks pre-cut from a sheet of cardboard, paperboard and the like, scrap adhering to said blanks, comprising a reciprocating plunger head; a set of punches mounted on said head for engaging the blanks of a sheet; a set of hold-down elements for engaging the scrap of the sheet; a die support underneath said plunger head, said support having apertures permitting the blanks to drop therethrough; a rotatable disk having therein a plurality of sets of die apertures, each set corresponding to a set of punches, said disk overlying said support; and means for rotating said disk for bringing said sets of die apertures successively into registry with said punches.

7. A machine for removing from blanks, pre-cut from a sheet of cardboard, paperboard, and the like, scrap adhering to said blanks, comprising a die plate support; a movable relatively thin die plate having apertures therein, the die plate being adapted to receive pre-cut sheets of board; means for forcing the blanks through said apertures and moving said die plate into engagement with said support while blanks are being forced through said die plate apertures; and means for moving said die plate from one position in which blanks are forced through its apertures into a different position for the removal of scrap therefrom.

8. A machine for removing from blanks pre-cut from a sheet of cardboard, paperboard, and the like scrap adhering to said blanks comprising a reciprocating plunger head; a plurality of punches mounted on said plunger head for engaging said blanks; hold-down means for engaging said scrap; a die plate support underneath said plunger head; a relatively thin die plate overlying said support, the die plate being deformable under the action of the punches on the

sheet without support and having die apertures therein corresponding with said punches; and means for moving said die plate into a first position of registry of its apertures with said punches for a punching operation and into a second position for removal of scrap resting on said plate.

9. A machine for removing from blanks pre-cut from a sheet of cardboard, paperboard, and the like, scrap adhering to said blanks, comprising a reciprocating plunger head; a plurality of punches mounted on said plunger head for engaging said blanks; a plurality of hold-down elements mounted on said plunger head for engaging said scrap; a relatively thin die plate movably mounted underneath said plunger head, the die plate having die apertures corresponding to said punches; a fixed die plate support beneath said plunger head for supporting said die plate against deformation during the punching operation, said support having apertures therein corresponding in location substantially to the apertures in said die plate and permitting blanks to drop therethrough; and means for moving said die plate relatively to said support into a first position of registry of its apertures with said punches and into a second position for removal of scrap from said plate.

10. A machine for removing from blanks pre-cut from a sheet of cardboard, paperboard, and the like, scrap adhering to said blanks, comprising, a punch for engaging a blank, the punch being smaller than the blank; a die plate having an aperture smaller than said blank, but larger than said punch; hold-down means for engaging said scrap; and means for moving said punch and said die plate relatively to each other for forcing said blank through said aperture.

11. A stripping machine for removing from blanks pre-cut from a sheet of cardboard, paperboard, and the like scrap adhering to said blanks, comprising, a plurality of punches for engaging said blanks, the punches being smaller than the blanks; a die plate having die apertures smaller than said blanks but larger than said punches; hold-down means for forcing said scrap against said die plate; and means for moving said punches to force said blanks through the apertures in said die plate.

12. A stripping machine for removing from blanks scrap pre-cut from a sheet of cardboard, paperboard, and the like, scrap adhering to said blank, comprising, a plurality of punches for engaging said blanks, the punches being smaller than the blanks; a movable die plate having die apertures smaller than said blanks but larger than said punches; hold-down means for forcing said scrap against said die plate; means for moving said die plate into and out of registry with said punches; and means for moving said punches to force blanks through said apertures.

13. A stripping machine for removing from blanks pre-cut from a sheet of cardboard, paperboard, and the like, scrap adhering to said blank, comprising, a plunger head; means for mounting said plunger head for reciprocating movement; a plurality of punches adjustably mounted on said plunger head, the punches being smaller than the blanks; a plurality of hold-down members adjustably mounted on said plunger head; a relatively thin die plate having die apertures therein smaller than said blanks but larger than said punches unless supported; means for mounting said die plate for movement into and out of registry with said punches; a rigid base; a

relatively thin top plate secured to said base, said base and top plate having apertures in fixed registry with said punches, the top plate being adapted to engage the underside of said movable die plate.

14. A stripping machine for removing from blanks pre-cut from a sheet of cardboard, paperboard, and the like, scrap adhering to said blanks, comprising, a plurality of punches; means for mounting said punches for reciprocating movement; a relatively thin die plate having die apertures therein, said die plate being deformable under action of said punches unless supported; means for mounting said die plate for movement into, and out of, registry with said punches, a rigid support adapted to engage the underside of said die plate; and yielding means for supporting said die plate normally out of engagement with said support and permitting said die plate to rest against said support when acted upon by said punches.

15. A stripping machine for removing from blanks pre-cut sheets of cardboard, paperboard, and the like, scrap adhering to said blanks, comprising, a plurality of punches; means for mounting said punches for reciprocating movement; a relatively thin die plate having die apertures therein, said die plate being deformable under action of said punches unless supported; a curved track for said die plate; means for mounting said die plate for movement into registry with said punches for stripping and out of registry with said punches onto said track for removal of scrap; a rigid support adapted to engage the underside of said die plate; and yielding means for supporting said die plate normally out of engagement with said support and permitting said die plate to rest against said support when acted upon by said punches.

16. A machine for removing from blanks pre-cut from a sheet of cardboard, paperboard, and the like, scrap adhering to said blanks, comprising, a plunger head; means for mounting said plunger head for reciprocating movement; a set of punches mounted on said plunger head for engaging the blanks of a sheet, said punches being smaller than said blanks; hold-down means on said plunger head for engaging the scrap of the sheet; a die support underneath said plunger head; a die member having therein a plurality of sets of die apertures, each set corresponding to said set of punches, said die member overlying said support, said die apertures being larger than said punches but smaller than said blanks; and means for moving said die member relatively to said support for bringing said die apertures successively into registry with said punches.

17. A machine for removing from blanks pre-cut from a sheet of cardboard, paperboard, and the like, scrap adhering to said blanks, comprising, a plunger head; means for mounting said plunger head for reciprocating movement; a set of punches mounted on said plunger head for engaging the blanks of a sheet, said punches being smaller than said blanks; a set of hold-down elements mounted on said plunger head for engaging the scrap of the sheet; a die support underneath said plunger head; a disk having therein a plurality of sets of die apertures, each set corresponding to said set of punches, said disk overlying said support, said die apertures being larger than said punches and smaller than said blanks; and means for rotating said disk for bringing said die apertures successively into registry with said punches.

LYLE E. SHANER.
